[57] CLAIM

The ornamental design for a fishing lure, as shown and described.

DESCRIPTION

FIG. 1 is a perspective view of the fishing lure with line and hook shown in phantom lines for environmental purpose;

FIG. 2 is a top plan view of the fishing lure;
FIG. 3 is a front elevational view of the fishing lure;
FIG. 4 is a right side elevational view of the fishing lure, the left side elevational view being a mirror image thereof;
FIG. 5 is a rear elevational view of the fishing lure; and
FIG. 6 is a bottom plan view of the fishing lure.

FIG. 1.

FIG. 2.

FIG. 3.

FIG. 4.

FIG. 5.

FIG. 6.
